ATTORNEY.

UNITED STATES PATENT OFFICE.

WILLIAM A. LIST, OF WHEELING, WEST VIRGINIA.

TIN-SEAMING MACHINE.

SPECIFICATION forming part of Letters Patent No. 309,551, dated December 23, 1884.

Application filed May 31, 1884. (No model.)

To all whom it may concern:

Be it known that I, WILLIAM A. LIST, a citizen of the United States, residing at Wheeling, in the county of Ohio and State of West Virginia, have invented or discovered certain new and useful Improvements in Tin-Seaming Machines, of which improvement the following is a specification.

In the accompanying drawings, which make part of this specification, Figure 1 is a perspective view of my improved seaming-tongs. Fig. 2 is a transverse sectional view showing the tongs clamping the edges of the tin sheets preparatory to bending over the projecting portion of one of said edges. Fig. 3 is a similar view showing the projecting portion turned over. Fig. 4 is a transverse sectional view showing the manner of using the tool for closing the seam. Figs. 5, 6, 7 show the different steps in the seaming operation.

My invention relates to that class of tools which are used for "locking" and "double locking" together the edges of strips of tin or other sheet metal employed in covering roofs. These strips are composed of a number of sheets soldered together. The longitudinal edges of the strips thus formed are turned up at right angles to the general plane of strips, one of said edges being made somewhat higher than the other. The strips thus prepared are laid alongside of each other on the roof or other surface to be covered, with the high edge of one sheet resting against the low edge of the adjacent strip. Then by suitable tools that portion of the high edge which projects above the adjacent low edge is bent down over and against said edge, thus locking or seaming the two strips together, and, if desired, this "locked" edge can be "double locked" or seamed by turning over the edges just locked, as is well understood in the art.

The object of my invention is to so construct a tool that this locking or seaming may be quickly effected without injury to the metal being operated on, and with comparative ease to the workman; and to this end my invention consists in the construction and combination of parts, all as more fully hereinafter described and claimed.

My roofing-tongs consist of the two metal jaws 1 and 2, nearly rectangular in cross-sec-

tion, and provided at each end with the upwardly-projecting ears 3, through which are passed the pins 4, thus hinging the two jaws together, as shown. To the sides of these jaws are secured the long lever-handles 13, by which said jaws are operated. The jaws are made of such a height that when they are clamped against two upturned edges, 7 and 8, of the strips the upper inside corners of the jaws are at least as high as the lower of the two upturned edges.

In the upper side of the jaw 1 is formed the recess 5, having one of its sides, 6, inclining downward and outward from the clamping-face of the jaw, as shown. That portion of the high upturned edge 8 which projects above the edge or flange 7 is, in the operation of the tool, bent upon the inclined side 6 by the turning-leaf 9, hinged on the upper side of the jaw 2 near its clamping-face. This turning-leaf is made triangular in cross-section, and is so hinged that it turns on its apex as a pivot, and its construction is such that when turned in the position shown in Figs. 2 and 4 its bending-face 10 will form an angle with the clamping-face of the jaw 2, to which it is hinged in order to give an initial bend to the projecting portion 11 of the flange 8 when the clamping-jaws are brought together. To this turning-leaf 9 is secured the treadle 14, by which the leaf is turned down into the position shown in Fig. 3, and thereby bending down the projecting portion 11 onto the side 6, as shown. This side 6 and the leaf 9 are so constructed with relation to each other that the projecting portion 11 is bent beyond a right angle to the flanges 7 and 8. The angle which the sides of the leaf 9 form at the apex is so obtuse that the other side of the leaf will overhang the turning-point when the leaf is turned to the position shown in Fig. 3, and the metal in said leaf is so disposed that the weight in this overhanging portion will cause the leaf to turn back into operative position as soon as the operator's foot is removed from the treadle. This return movement of the leaf will be assisted by the resiliency of the turned-down portion of the metal strip.

The seaming-tools now in use have the under sides of the clamping-jaws at right angles to the clamping-face, and when so constructed

it is impossible to open the clamping-jaws without bending up the turned-down portion 11 if said portion has been bent beyond a right angle to the flanges 7 and 8, as is always desirable. I overcome this objectionable feature by cutting away the under face of the clamping-jaws, as shown, so that said jaws when clamped on the upturned edges 7 and 8 will rest on the flat portion of the strips at its outer corners only, and consequently when the jaws are opened the inner corners of the jaws will drop down, so the jaw 1 can move out from under the portion 11 without bending said portion up in the slightest degree.

In using seaming-tools the projecting portion 11 is frequently broken or torn immediately in front of the tool when the turning-leaf bends down that part on which it is operating, as will be readily understood. This breaking or tearing of the projecting portion is avoided in my tool, as the operative face 10 of the leaf 9 is concaved at each end, as shown at 12, Fig. 1, thereby providing for a gradual bending of the portion 11 at the forward end of the tool, and avoiding the sharp bend which is given to said portion when the operative face of the turning-leaf is uniform throughout its whole length, as will be readily understood. The inner edges of the ears 3 are cut away, as shown, so as to permit of the entrance and bending of the portion 11 of the flanges. After the projecting portion has been bent as shown

in Fig. 3, it is closed down against the lower flange, 7, by closing the clamping-jaws against this turned portion 11, when it will be closed, 35 as shown in Fig. 4.

If it is desired to form a double seam, a tool similar to the one above described is used, with the exception that the clamping-jaws should be made lower than those shown by an amount 40 equal to the width of the portion to be bent in forming the double seam. It will be noticed that in closing down the bent portion 11 the tool does not have to be reversed, as is the case with other tools of this class, except those in 45 which one half of the tool is employed for forming the initial bend and the other half for closing down the portion bent at the previous operation of the tool; but this simultaneous bending and closing operation requires considerable exertion on the part of the operator.

I claim herein as my invention—

In a seaming-tool, a pair of hinged clamping-jaws, one of said jaws having the inclined face 6, and both jaws having their under faces inclined as described, in combination with a turning-leaf, substantially as set forth.

In testimony whereof I have hereunto set my hand.

WILLIAM A. LIST.
